UNITED STATES PATENT OFFICE.

AUGUST HUSSON, OF OSHKOSH, WISCONSIN.

SHADE-ROLLER LOCK.

1,034,457.

Specification of Letters Patent.

Patented Aug. 6, 1912.

Application filed June 9, 1911. Serial No. 632,111.

To all whom it may concern:

Be it known that I, AUGUST HUSSON, a citizen of the United States, residing in Oshkosh, in the county of Winnebago and 5 State of Wisconsin, have invented new and useful Improvements in Shade-Roller Locks, of which the following is a description, reference being had to the accompanying drawings, which are a part of this specification.

10 This invention has for its object to provide means which will prevent the stripping of a window shade from its roll.

It is the common practice to attach a window shade to its roll by means of tacks or 15 other securing devices and when the shade is drawn down too far, it is liable to be torn from the tacks or attaching devices and is thus detached from the roll.

The present invention is designed to afford 20 a means for limiting the extent of the unwinding of the shade from the roll and thus prevent its being torn from its attaching means.

Another object of the invention is to limit 25 the extent to which the shade may be wound upon its roll and thus determine the position to which it may be raised when it is desired to prevent the shade being raised to the height of the shade roll.

30 With the above and other objects in view the invention consists in the window shade stop as herein claimed and all equivalents.

Referring to the accompanying drawings in which like characters of reference indicate the same parts in the different views. Figure 1 is a front elevation of a window shade provided with a stop constructed in accordance with this invention; Fig. 2 is an end view thereof; Fig. 3 is a sectional detail view of the stop mechanism showing the 35 position of the parts when the shade is raised; Fig. 4 is an end view showing the position of the locking dogs at such time; Fig. 5 is a transverse sectional view through the stop mechanism showing the position of the stop pins at such time; Fig. 6 is a sectional plan view similar to Fig. 3 showing the parts in the position for stopping the downward movement of the shade; Fig. 7 40 is a corresponding view of the locking dog mechanism thereof at such time; and, Fig. 8 is an end elevation of the shade roll with the screw stem sectioned.

In these drawings 10 indicates a window 45 shade attached to and wound upon a shade roll 11 in the usual manner and said roll

containing the ordinary winding spring with its flattened stem 12 supported and held against turning by the slotted bracket 13 as usual. Instead of a plain trunnion bearing at the right hand end of the shade roll, a stop device is let into a recess 14 in the end of the rod and which stop device will now be described in detail. A casing, 50 preferably comprising a strip of sheet metal 15 bent and formed into a substantially cylindrical shape with its ends secured to a disk-shaped end plate 16 by having tongs passing therethrough and bent down thereon, fits within the opening 14 in the end of the shade roll and may be held by tacks 17 driven through the end plate 16 into the end of the shade roll. A screw rod 18 has its reduced inner end journaled in an opening through the inner end of the casing and 55 is desirably upset to prevent its withdrawal therefrom. Said rod is also journaled in a central opening through the end plate 16 and has a flattened portion 19 which fits in a slotted bracket 20, corresponding to the 60 bracket 13 at the other end of the shade roll. The end of the screw rod 18 extends somewhat beyond the flattened portion 19 to constitute a projecting handle by means of which the rod may be conveniently turned in its 65 bearings when detached from the slotted bracket 20. The edges of the strip of sheet metal forming the casing 15 are spaced apart and form parallel walls of a guide slot 21. A nut 22 is threaded on the screw rod 18 with- 70 in the casing and is provided with a projecting key lug 23 which rides in the guide slot 21 and prevents the nut from turning on the screw rod but permits it to travel from one end of the casing to the other as 75 propelled by the thread of the screw rod. The nut 22 has a stop pin 24 on one side thereof and a stop pin 25 on the other side, the former being adapted to come into engagement with a stop pin 26 on the inner 80 end of the screw rod and thus limit the inward movement of the nut and the stop pin 25 being adapted to come into engagement with a stop pin 27 near the other end of the screw rod to limit the outward movement of 85 the nut.

In applying a shade equipped with this stop device, the desired tension is given to the winding spring as usual and then the shade is drawn off the roll to the full extent which is necessary for its use, but which is less than its entire length, and the 90

screw rod 18 is turned by hand in the direction to cause the nut 22 to travel inwardly to engage the stop pins 24 and 26. In this position of engagement of the stop pins 24 and 26 it will be impossible to enter the flat portion 19 of the screw rod in the slot of the bracket 20 because in positioning the casing in the end of the shade roll, care is taken that with the parts in this condition the flattened portion of the screw rod will differ in angular position by a quarter turn from the position of the flattened portion of the spring stem 12. This necessitates the screw rod 18 being turned back a quarter turn to permit its flattened portion 19 to enter the slot of the bracket 20 for a purpose which will be later mentioned. With the shade roll mounted in both brackets, the shade may be raised and lowered as usual with this exception, that when the shade reaches the predetermined position to which it was drawn when adjusting the stop device, it will become automatically locked against further downward movement. As the shade at such time has not been entirely unwound from the shade roll, the strain incident to the sudden stopping thereof is not exerted on the attachment of the shade to the roll and there is therefore no danger of such attachment giving way. This action of stopping the shade automatically at the desired position results from the travel of the nut 22 in the casing during the movements of the shade, the upward movement of the shade causing the nut to travel from left to right and the downward movement of the shade causing the nut to travel in the opposite direction and being finally limited by the engagement of the stop pins 24 and 26.

When it is desired to limit the position to which the shade may be raised, the device is so adjusted that the stop pins 25 and 27 engage at the desired extreme position of the shade, the screw rod being turned by hand while the shade is in this position as before.

The difference in angular position of the flattened portion of screw rod 18 and the flattened portion of the spring stem 12 when the former is locked by the engagement of the stop pins and the latter is locked by the engagement of the dogs, assures a sufficient play for the shade when in the position in which it is locked to permit of the disengagement of the dogs. If the dogs should engage at the same time that the

stop pins engage it is obvious that the shade roll could not be turned to disengage the dogs, but at such time the dogs are out of engagement as shown in Figs. 6 and 7, so that the release of the shade from its locking position is not interfered with.

While a specific construction has been shown and described in detail for the purpose of exemplifying the invention, I do not wish to be understood as confining myself thereto, except as such limitations may be contained in the respective claim, for it is obvious that the principles involved are capable of embodiment in various forms. Furthermore, while the invention has been explained as applicable to window shades, it is capable of performing the desired functions in various other applications, such as in map holders, curtain rollers and the like, and consequently the term "shade roll" as herein employed for convenience is to be understood as comprehending all of such other devices to which the invention may be applied to serve one or more of the useful purposes mentioned.

What I claim as new and desire to secure by Letters Patent is:

In a shade roll or the like, a housing comprising a strip of sheet metal bent to a U-shape with its edges turned inwardly to form a cylindrical casing with a guide slot between said inturned edges, an end plate secured to the ends of the strip, said casing being adapted to fit within the end of the shade roll and turn therewith, a nut slidably mounted in the casing, a key lug on the nut passing through the guide slot of the casing to cause the nut to turn with the shade roll, a screw rod journaled through the end plate of the casing and having its end reduced and journaled in the inner end of the casing, said screw rod being threaded within the nut and having a flattened portion outside of the casing, a slotted bracket engaging the flattened portion of the screw rod, said screw rod continuing beyond the flattened portion to form a handle by means of which it may be turned, stop pins on the nut, and stop pins on the screw rod to be engaged by the stop pins on the nut for limiting the movements of the shade roll.

In testimony whereof, I affix my signature, in presence of two witnesses.

AUGUST HUSSON.
